UNITED STATES PATENT OFFICE.

ALONZO L. HILDRETH AND ALEXANDER M. McLENDON, OF SAVANNAH, GEORGIA.

CLEANING-MACHINE.

1,381,553.

Specification of Letters Patent. Patented June 14, 1921.

Application filed April 19, 1920. Serial No. 374,981.

To all whom it may concern:

Be it known that we ALONZO L. HILDRETH and ALEXANDER M. McLENDON, both citizens of the United States, and both residing 5 in Savannah, in the county of Chatham and State of Georgia, have jointly invented certain new and useful Improvements in Cleaning-Machines, of which the following is a specification.

10 The object of this invention is to provide a simple, inexpensive, and efficient machine for cleaning garments, cloths, pieces of fabrics, etc.

15 In carrying out our invention, we use a table of simple construction, and in the top thereof we mount two rotary brushes, one of which is employed to remove dust from the article operated upon, and the other to remove spots or stains therefrom.

20 The dusting brush is mounted in a casing which is connected with an exhaust pump or fan, and the other brush is mounted in a small tank or receptacle containing a cleansing fluid. Gearing is provided for driving 25 the brushes and the fan, and the dusting brush, which extends a short distance above the table top, is divided into sections in order to more efficiently operate on the article being cleaned and to permit the exhaust 30 mechanism to better perform its functions. In order to support and guide the article being cleaned while passing over the dusting brush, we employ rods or wires which bridge the opening in the table through which the 35 dusting brush extends and which are arranged between the brush sections in such manner as to permit the bristles to properly operate upon the cloth while the latter is properly supported and held in the best condition for cleaning purposes. 40

Our improvements are illustrated in the accompanying drawings, in which:—

Figure 1 is a top plan view of the machine.

Fig. 2 shows a section on the line 2—2 of

45 Fig. 1.

Fig. 3 is a section on the line 3—3 of Fig. 1.

Fig. 4 is a detail view in perspective of the casing of the dusting brush.

Fig. 5 is a perspective view of a section of 50 the brush.

The table A may be of any suitable construction. The top *a* of the table is supported by the legs *a'*, and held at the desired elevation. A tank B for containing a cleansing 55 fluid *b* is attached to the underside of the table top below an opening *a*² therein which

is preferably located near one corner of the table. Within the tank is located a rotary brush C secured to a shaft *c* carrying a pulley *c'* by which it is driven. The brush extends a short distance above the top of the table as indicated in Fig. 2. The brush C is adapted to clean parts of the clothes or fabrics which are spotted or stained and, therefore, may be of relatively small dimensions. 60

A relatively large opening D is made in the table top and is preferably located centrally thereof and below this opening there is a casing E of general cylindrical form. It is open at the top, closed at opposite ends, 70 and connected at its lower end with an exhaust pipe F leading to an exhaust pump or fan G. The upper edge *e* of the casing on one side of the top opening extends to the top of the table or a short distance above it, 75 while the opposite edge *e'* extends a considerable distance above the table top.

A shaft H extends through the casing and carries a series of brushes L, which are held a short distance apart on the shaft. Each 80 of these brushes is cylindrical in general form and is divided into sections, as shown by intervening spaces *l*. Bridge wires M are arranged across the opening D. One end of each wire is attached to the lower 85 edge *e* of the casing and the other end crosses the elevated edge *e'* thereof. Each wire is bent as indicated at *m* and rests on the top of the table. There is preferably a bridge wire between each two brushes and 90 a bridge wire at each end of the casing.

The shaft H is supported in suitable bearings *h* and one end is extended beyond the side of the table and carries a driving pulley N operated by the belt N'. The shaft H 95 also carries a pulley O belted to the fan G and a pulley P belted to the pulley *c'* on the shaft *c* of the brush C. Said shaft *c* is mounted in suitable bearings *x* as indicated in Fig. 1. 100

All working parts of the apparatus are operated by the belt N' and the gearing is such as to give proper relative speeds to the two brushes and the fan.

The machine is adapted to operate upon 105 garments of various kinds, upon pieces of cloth, and various kinds of fabrics. The article is placed on the table, preferably being moved from the right hand end thereof, as shown in Figs. 1 and 2, over the dusting 110 brush. While being moved over the dusting brush, the article is supported by the bridge

wires M and held in a smooth and level condition. The bristles of the brushes L extend upwardly between the bridge wires as indicated in Fig. 2 and operate most 5 efficiently upon the cloth to loosen the dust therein, the loose dust being drawn by the exhaust mechanism through the pipe F and expelled in obvious ways. The cloth may be passed back and forth over the dusting 10 brush until dust is entirely removed therefrom, then if there be any spots on the material these may be removed by placing the spotted or stained part of the cloth over the brush C while the latter is rotating. 15 This brush applies the cleansing fluid to the spots and at the same time exerts a brushing action thereon.

Experience has demonstrated that a machine constructed and operated in the manner above described is most efficient. It can 20 be built at small cost and operated at small expense.

We claim as our invention:—

1. A cloth cleaning machine, comprising 25 a table, having an opening in its top, a rotary brush extending upwardly through said opening, a casing for the brush secured to the under side of the table, bridge wires extending upwardly and rearwardly from 30 their front ends across the opening for supporting the cloth while being cleaned above

the plane of the table, and exhaust mechanism connected with the lower portion of the casing below the brush for drawing air through the cloth and the bridge wires 35 while supported by said wires and while being acted on by the brush.

2. A cloth cleaning machine, comprising a table having an opening in its top, a rotary sectional brush extending upwardly 40 through said opening, a casing for the brush secured to the under side of the table having an opening at the top and having its upper front edge flush with the top of the table and its rear edge above the top of the table, 45 bridge wires extending across the opening for supporting the cloth while being cleaned, the front ends of which are supported by the front edge of the casing and the rear portions of which are supported by and ele- 50 vated by the rear edge of the casing, and exhaust mechanism connected with the lower portion of the casing below the brush for drawing air through the cloth and under the bridge wires while the cloth is being 55 supported by said wires and being acted on by the brush.

In testimony whereof, we have hereunto subscribed our names.

ALONZO L. HILDRETH.
ALEXANDER M. McLENDON.
